Primary Examiner — Michelle E. Wilson*Assistant Examiner* — Sanjeev Paul(57) **CLAIM**

The ornamental design for audio eyeglasses, substantially as shown and described.

DESCRIPTION

FIG. 1 is a perspective view of a set of audio eyeglasses as seen from the front, top, and right side;

FIG. 2 is front view thereof;

FIG. 3 is a right view thereof;

FIG. 4 is a back side view thereof;

FIG. 5 is a left side view thereof;

FIG. 6 is a top view thereof; and,

FIG. 7 is a bottom view thereof.

The dotted line portions of the drawings represent environmental structure only and do not form part of the claimed design.
